Inventor

James S. Ostrander

United States Patent Office.

JAMES S. OSTRANDER, OF ALBANY, NEW YORK.

Letters Patent No. 91,766, dated June 22, 1869.

IMPROVEMENT IN ROLLER-CASES FOR MAPS AND CHARTS.

The Schedule referred to in these Letters Patent and making part of the same.

To all whom it may concern:

Be it known that I, JAMES S. OSTRANDER, of the city and county of Albany, State of New York, have invented certain new and useful Improvements in the Mode of Constructing, Arranging, and Operating Rollers for Preserving and Exhibiting Songs, Sheet-Music, Maps, or other articles of similar nature; and I do hereby declare that the following is a full, clear, and exact description thereof, reference being had to the accompanying drawings, in which—

Figure 1 represents a perspective view of the invention.

Figure 2 is a longitudinal vertical section of the same.

Figure 3 is a cross-section of the same.

Figure 4 is a view through red line No. 5, in fig. 2, viewed towards the side of the box.

It is desirable, and of great advantage in many cases, to be able to exhibit at will any one of a collection of songs, sheet-music, maps, charts, and the like, to scholars or others, without the inconvenience of hanging or unhanging any of the said articles to be examined or referred to, which articles generally require (especially in schools, academies, and colleges) some conspicuous place, for proper exhibition to all interested therein.

Several devices have been used, whereby the said articles could be conspicuously displayed at will, but they do not possess all that is desirable to make their use general or practical in many cases.

By my invention, Sabbath or other school-rooms, lecture-rooms, public halls, private studies, dwellings, and offices, may possess and afford opportunity for the exhibition of a great variety of subjects for consideration or lessons for practice, and any and all of which subjects (if represented) could be under the ready and direct control of the instructor, lecturer, or exhibitor.

The nature of my invention consists in using rollers, provided with feathered spindles on one of their ends, and working into slotted bearings, provided with a projecting piece, facing the ends of the roller, whereby the rolling or unrolling of the curtain-material or the like thereon may be stopped at any point desired.

The said rollers may be placed in one or more rows in a box, which may be supported by brackets, or otherwise, from a wall, partition, or any other place in a room which might be desirable.

To enable others skilled in the art to make and use my invention, I will proceed to describe it, in reference to the drawings, and the letters of reference marked thereon, the same letters indicating like parts.

A, figs. 1, 2, 3, and 4, represents a box furnished with a permanent cover, A', in which are to be placed the rollers B, furnished with maps, hymns, sheet-music, and the like, to be exhibited.

The said box may be secured to the ceiling, by screws or other equivalent devices, as in fig. 2, or may be secured to a wall or partition, from its back side, as in fig. 3, or may be supported by brackets, not shown.

The rollers B are inserted in their places from the lower and open side of the box A, and are placed in

rows, two or more, one above the other, as shown in fig. 3, and in such a manner as will cause the fall of the material No. 1 (to be exhibited) to pass clear of that of No. 2, and No. 3 clear of No. 4, and so on, so that the surface of the material, rolled or unrolled from above, will not rub against those below.

This is essential, especially in stencilled hymns, songs, and music-lessons, where the ink of the one would be apt to rub on the surface of the other, and thus mar or discolor the surfaces in contact.

To prevent the unrolling of the material from the rollers, and to hold in view a limited portion of the said material, with its map or lesson, and the like, thereon, I make, on the spindles b, figs. 1, 2, and 4, the feathers c, which act against the stops e, secured to the inside of the end of the box, as shown in figs. 1 and 4.

The spindles b work in the slots S, made in the end of the box, as shown in figs. 1 and 4; and when any of the rollers are to be removed, they are so turned as will bring the feather c, on the spindle b, in position of c, No. 2, when the roller is pushed endwise toward the slot S, and drawing the spindle b of the roller out of its bearing, and lopping it down, the feathered spindle is drawn back from its bearing and the roller is released. To insert the rollers, the operation is reversed.

When the rollers are at rest, their centre lines (red line, No. 1,) are slightly deviated from a horizontal line, (red line, No. 2;) and to be operated for rolling or unrolling, their centres are to be raised, at their feathered spindle-ends, slightly above the horizontal line to that of red line No. 3.

The spindles b of these rollers are furnished with squared ends, and are intended to be operated by a device invented by myself, and termed "the winding staff."

To operate this invention, the lessons, maps, songs, and the like, to be exhibited, are properly attached to the rollers B, and rolled thereon, as shown in fig. 3, so that those on the upper rollers will fall clear of those on the lower, ones when the wrench, or key of "the winding-staff," is slipped on the squared end of the spindle b of the roller to be operated, and slightly elevated in position of red line No. 3, fig. 2, so that the feather c will be thrown out of contact with the stop e, when the said roller can be revolved in either direction, as may be desired; and when a sufficient portion of the material thereon has been rolled or unrolled, the roller is allowed to drop down to line No. 1, when it will be fixed so as to unroll no further.

Having described my invention,

What I claim, and desire to secure by Letters Patent, is—

In combination with the rollers B, the feathered spindles c, stops e, and slotted bearings S, substantially as and for the purposes set forth.

JAMES S. OSTRANDER.
